(57) **CLAIM**

The ornamental design for a locking device, as shown and described.

DESCRIPTION

FIG. 1 is a front perspective view of a locking device illustrating our new design.

FIG. 2 is a rear perspective view of a locking device illustrating our new design.

FIG. 3 is a front view of a locking device illustrating our new design.

FIG. 4 is a rear view of a locking device illustrating our new design.

FIG. 5 is a left side view of a locking device illustrating our new design.

FIG. 6 is a right side view of a locking device illustrating our new design.

FIG. 7 is a top view of a locking device illustrating our new design; and,

FIG. 8 is a bottom view of a locking device illustrating our new design.

Portions of the locking device illustrated with broken lines in the figures are unclaimed portions of the locking device shown for illustrative purposes only and form no part of the claimed design.

1 Claim, 4 Drawing Sheets
